Louis Bayha and Frederick Rapp

Sixty-ninth Patent

The Schedule referred to in their Letter Patent and making part of the same containing a description in the words of the said Louis Bayha and Frederick Rapp themselves of their improvement in the machine for cutting Meat.

Be it known that we Louis Bayha and Frederick Rapp of Wheeling the County and State of Virginia have made an improvement in the machine for cutting Meat which is described as follows. This machine consists of a frame which supports the machinery and horses, a carriage and block on which the meat is placed and cut. Horses for cutting the meat and the arms and levers by which they are worked. a cylinder containing projections, which serve the horses. a cog wheel head wheel and pinion which moves the rack and carriage. and a rack and segment wheel for moving the carriage. The frame is constructed by mortising and tenoning together four rails, four uprights, two girders and two cap pieces, from the top two arms project to raise the end of the carriage placed over the arms of the horses. also on the top is placed a rail having partitions in it through which the before mentioned levers work. This frame is about 6 feet high 6 feet long and 3 feet wide. The carriage and block. The carriage is about 3 feet long 20 inches wide and 16 inches deep. The sides and ends are smooth and can be taken off. At one end of the carriage are arms about 2 1/2 feet long which applied the rack and segment wheel to be hereinafter described.

The block on which the meat is cut is about 10 feet 2 inches long 18 inches wide and 16 inches deep. It is placed upon the carriage and when worn can be raised up and is about 14 inches above the bottom of the carriage. The carriage with the block

are placed upon rollers resting on the sills of the frame. The knives and arms & levers for moving them. There may be from four to sixteen knives, more or less. each knife is about 13 inches long and 6 inches deep made of the best steel with a sharp cutting edge. it is fastened by bolts or screws to an arm about $3\frac{1}{2}$ feet or 4 feet long. a peg or projection is put on each arm about 2 feet from the knife. it is made each to work through an opening in a cross piece. A lever is placed over each arm and knife having a weight on it for giving force to the knife. This lever turns on a pivot placed on the frame. The knife is raised about 8 or 9 inches by the projections on the cylinder to be hereafter described. The cylinder containing the projections rising which work the knives. The cylinder extends the length of the frame and about 6 or 8 inches in diameter. It turns on a pivot in the frame by means of a cross. the arms of this pivot turn upon this cylinder in a spiral direction so that each knife will be raised twice at each revolution of the cylinder stem. A Cog Wheel, Ravel Wheel and Pinion, which move the racks and carriage by two racks and segment wheel placed between them. A pinion placed on the end of the cylinder turns a cog wheel turning in guides in the frame. This turns a miter wheel by a bevel wheel fixed on the same axle as the cog wheel. The miter wheel is fixed on an axle or shaft about 4 feet long. On the lower end of this shaft is a segment cog wheel which works in two racks one on each side and moves the carriage forward and backward. Operation. The meat to be cut is placed on the block in the carriage. Motion is given to the cylinder by any convenient power. the pegs on the cylinder give motion to the knives by raising the arms. the weight on the levers placed over the arms send them down with force. The pinion on the end of the cylinder gives motion to the cog wheel. the bevel wheel on its axle gives motion to the miter wheel. this gives motion to the segment wheel at the lower end of the shaft which works into the racks placed on each side of it alternately which move the carriage

forward and backward, and carry the meat forward. The
cylinder here claimed and desired to be named by the inventor
as the before described machine for cutting Game or meat, further
shows the cylinder with the flags or projections fixed especially
forming the arms. The legs and weight placed on the arms
and the segment wheel working thereby, that moves the arms
forward and backward. For a further illustration of our
invention, we refer to the model and drawing of the same deposited
in the Patent Office. — In testimony whereof we have
subscribed our names before witnesses this 20th day of

March 1833
